UNITED STATES PATENT OFFICE

ONNI S. KOSKINEN, OF DETROIT, MICHIGAN

GRINDING MACHINE

Application filed March 28, 1928. Serial No. 265,315.

My invention relates to a new and useful improvement in a grinding machine adapted for grinding dies, punches, etc.

It is an object of the present invention to provide a machine of this class which will be simple in structure, economical of manufacture and highly efficient in use.

In grinding the dies it is my intention to use a guide surface from which the grinding surface of the grinding wheel will be guided and the present invention is to provide a grinding machine having a guide member mounted thereon for engaging the guide surface.

15 In carrying out this method of grinding it is desirable that the contacting member which engages the guiding surface shall not be of the same diameter as the grinding wheel, and it is an object of the present invention to provide a dressing tool and means for holding and adjusting the same so that the periphery of the contacting member may be ground to a size bearing a relation to the diameter of the grinding wheel.

20 Other objects will appear hereinafter.

The invention consists in the combination and arrangement of parts hereinafter described and claimed.

The invention will be best understood by a reference to the accompanying drawings which form a part of this specification, and in which,

Fig. 1 is a side elevational view of the invention.

35 Fig. 2 is a view taken on line 2—2 of Fig. 1.

Fig. 3 is a sectional view taken on line 3—3 of Fig. 2.

Fig. 4 is a fragmentary view taken on line 4—4 of Fig. 3.

40 Fig. 5 is a view taken on line 5—5 of Fig. 3.

In the drawings I have illustrated the invention used with a supporting standard 9 upon which is slidably mounted the bed 10 carrying the housing 11 upon which the work retainer 13 is positioned, shielded by the

guard member 12, the workpiece 14 being held by the retaining member 13 in a well-known manner. Mounted upon the upper end of the standard 9 is a bracket 15, positioned above which is a cage 16 of an electrical motor 17. The shaft 18 of the motor is fixedly attached to the pulley 19 which is connected by the belt 20, enclosed by the belt guard 21, to the pulley 22 which is fixedly mounted upon the shaft 23, this shaft projecting into a passageway 24' formed in the housing 24.

A thrust bearing 24" engages the shaft 23, adjacent one end of the passage 24', and a sleeve 25 is threaded into the lower end of the passage and serves as a bearing for the tapered end of the shaft, this sleeve 25 having oil passages 26 formed therein.

Threaded on the lower end of the sleeve 25 is a collar 27 having the inwardly projecting flange 28 adapted to overlap so as to engage the undersurface of the flange 29 which projects outwardly from the upper end of the collar 30. Mounted on the lower end of the collar 30 is a guide contact ring 31. A grinding wheel 32 is fixedly mounted on the lower end of the shaft 23. Threaded into the collar 30 is a set screw 33 whereby this collar may be caused to rotate in unison with the shaft 23. When it is desired that the collar 30 remain stationary, relatively to the shaft 23, while the same is rotating, the set screw 33 will be removed and the collar 27 threaded onto the member 25 so as to clamp the upper end of the collar 30 in engagement with the lower end of the member 25.

It is of course evident that when it is desired to have the collar 30 rotate with the shaft 23, the set screw 33 will be used and the collar 27 unscrewed slightly to permit the necessary play of the flange 29 so that a free and easy rotation relatively to the collar 27 may be effected.

Mounted on the housing 24 is a housing 34 in which is slidably mounted a square shaft 35 to which is attached a nut 36 in which is

threaded the stem 37, this stem being supported by and journalled in the upper end 38 of the housing. A bevel gear 39 is fixedly mounted on the stem 37 and adapted to mesh with the bevel gear 40 fixedly mounted upon the shaft 41, upon which is fixedly mounted the hand wheel 42 to effect a rotation of the gear 40 and the stem 37 so as to raise and lower the member 35 in the housing 34. The lower end 43 of this member 35 is reduced and projects through the plate 44. Formed on the lower end of the portion 43 is a reduced head 45 upon which is swivelly mounted a housing 46, this housing being clamped on the head by a bolt projected through the split portion 47. Slidably mounted in the housing 46 is a barrel 48 in which is threaded the set screw 49 adapted to engage the diamond dressing tool 50 which is inserted in the barrel 48. Threaded through the end of the housing 46 is a screw 51 having a knurled head 52 formed thereon, this screw being swivelly connected to the barrel 48 so that a threading of the screw 51 will effect an axial movement of the barrel 48 relatively to the housing 46 so that the dressing tool may be moved toward and withdrawn from the periphery of the grinding wheel 32. By raising and lowering this dressing tool while the grinding wheel is rotating, it is evident that a dressing of the grinding wheel may be effected.

Mounted on the housing 24 is a housing 53 in which is slidably mounted the shaft 54 having a reduced portion 55 projecting outwardly from the housing through the plate 56. Swingably mounted on the head 57 formed on the reduced portion 55 and adapted to be clamped thereon at will is a housing 58 in which is slidably mounted the tool retaining barrel 59 in which is threaded the set screw 60 for engaging the guide dressing tool 61. A stem 62, resembling the stem 51, is swivelly connected to the barrel 59 and projected exteriorly of the housing and provided with a knurled head 63 which is provided on one face 64 with graduations corresponding to the graduations on the periphery of the housing 58. Secured to the member 54, adjacent the upper end, is a nut 65 in which threads the stem 66 which is depended from and journalled in the top 67 of the housing 53. A bevel gear 68 is fixedly mounted on the stem 66 meshing with a bevel gear 69 mounted fixedly on the shaft 70 on which is fixedly mounted the hand wheel 71.

By a rotation of the hand wheel 71, the dressing tool 61 may be moved axially of the grinding wheel 32 and guiding ring 31.

As shown in Fig. 4, the housing 34 is rockingly mounted by means of the screw 72 on the housing 24, so that the diamond 50 may be inclined to the diameter of the grinding wheel 32 to taper the grinding wheel.

A screw 73 is provided with a head 74 which engages in a recess 75 formed in the housing 34 and is provided with a nut 76 whereby the housing may be locked in its various positions of tilt.

As shown in Fig. 2, the housing 53 is secured by suitable screws 77 in fixed relation to the housing 24.

In operation the diamond 50 may be adjusted to the desired position and moved axially of the housing 34 for dressing the grinding tool 32.

When it is desired to use the grinding wheel 32 for grinding the workpiece 14 the contact guide ring 31 is brought into engagement with a guide strip 78 which is fixedly mounted upon the upper surface of the workpiece 14 so as to have one face projecting outwardly beyond the face of the workpiece to be ground, or positioned inwardly from it, as desired.

The contact guide ring 31 engages this guide surface and serves to guide the grinding wheel 32 relatively to the workpiece 14.

The distance of displacement between the guide surface and the surface of the workpiece to be ground will in all cases be known, and consequently, after the grinding wheel has been ground, the guide ring may be faced and dressed to the proper diameter. In order to do this, the dressing tool 61 is brought into engagement with the periphery of the grinding wheel 32, after the grinding wheel has been dressed. The guide dressing tool 61 is then moved upwardly so as to engage in the space between the upper face of the grinding wheel and the contact guide ring, shown in Fig. 3. The nut 63 may then be turned, using the graduations as a guide, so as to project the dressing tool 61 inwardly, or withdraw it, as the case may be, a distance corresponding to the distance of displacement of the relative surfaces. When this has been done, the dressing operation on the contact guide ring may then be effected so that when the grinding operation is accomplished with the contact guide ring in engagement with the guide strip 78, the face of the workpiece 14 will be of the contour and dimensions desired.

The barrel 48 is prevented from rotating in the housing 46 by means of the block 79 which engages the flat 80 formed on the periphery of the barrel. A similar block 81 engages a similar flat formed on the barrel 59.

It is thus seen that I have provided a mechanism whereby the contact guide ring may be dressed in proportion to the size of the grinding wheel and also whereby the grinding wheel may be dressed to a tapered or cylindrical shape.

While I have illustrated and described the preferred form of my invention, I do not wish to limit myself to the precise details of

structure shown, but desire to avail myself of such variations and modifications as come within the scope of the appended claims.

Having thus described my invention, what I claim as new and desire to secure by Letters Patent is:

1. A grinding machine of the class described, comprising: a grinding member; a guide contact member; a dressing tool for dressing the periphery of said guide contact member; and means for adjusting the position of said tool in co-ordination to the periphery of said grinding member.
2. In a grinding machine of the class described, a grinding wheel; a guide contact member; a tool carrying member; a tool mounted in said tool carrying member for dressing the periphery of said guide contact member; and means for adjusting the position of said tool carrying member relatively to the periphery of said grinding wheel for determining a predetermined relative location of the peripheries of said guide contact member and said grinding wheel.
3. In a grinding machine of the class described, a grinding wheel; a guide contact member; means for securing said guide contact member to rotate in unison with said grinding wheel; and means for retaining said guide contact member non-rotatable upon rotation of said grinding wheel.
4. In a grinding machine of the class described, a grinding member; a guide contact member arranged concentrically of said grinding member; means for dressing the periphery of said guide contact member; and means for adjusting the position of said dressing means in co-ordination to the periphery of said grinding member.
5. In a grinding machine of the class described, a shaft; a grinding wheel mounted on said shaft and rotatable therewith; a bearing for said shaft having a threaded periphery and normally stationary upon rotation of said shaft; a collar mounted on said shaft and movable axially thereof and rotatable thereon; a guide contact member mounted fixedly on said collar; means for locking said collar on said shaft for rotation in unison therewith.
6. In a grinding machine of the class described, a shaft; a grinding wheel mounted on said shaft and rotatable therewith; a bearing for said shaft having a threaded periphery and normally stationary upon rotation of said shaft; a collar mounted on said shaft and movable axially thereof and rotatable thereon; a guide contact member mounted fixedly on said collar; means for locking said collar on said shaft for rotation in unison therewith; and means upon release of said locking means for moving said collar axially of said shaft and locking the same against rotation thereon.
7. In a grinding machine of the class de-

scribed, a shaft; a grinding wheel mounted on said shaft and rotatable therewith; a bearing for said shaft having a threaded periphery and normally stationary upon rotation of said shaft; a collar mounted on said shaft and movable axially thereof and rotatable thereon; a guide contact member mounted fixedly on said collar; means for locking said collar on said shaft for rotation in unison therewith; and means threadable on said bearing and engaging said collar for locking the same against rotation.

In testimony whereof I have signed the foregoing specification.
